US0D1076387S

(12) United States Design Patent (10) Patent No.: US D1,076,387 S
(45) Date of Patent: * May 27, 2025

(54) SHOE

(71) Applicant: NIKE, Inc., Beaverton, OR (US)

(72) Inventor: Minuk You, Portland, OR (US)

(73) Assignee: NIKE, Inc., Beaverton, OR (US)

() Term: 15 Years

(21) Appl. No.: 29/908,546

(22) Filed: Jan. 12, 2024

(51) LOC (15) Cl. 02-04

(52) U.S. Cl.

USPC D2/972

(58) Field of Classification Search

USPC D2/902, 907-908, 915, 946, 947, 969,

(57) CLAIM

The ornamental design for a shoe as shown and described.

DESCRIPTION

FIG. 1 is a side view of a shoe showing my new design;

FIG. 2 is a rear perspective view thereof;

FIG. 3 is a rear view thereof;

FIG. 4 is an opposite side rear perspective view thereof; and,

FIG. 5 is an opposite side view thereof.

The broken lines immediately adjacent to the shaded area define the bounds of the claimed design and form no part thereof. The broken lines depicting the remainder of the shoe form no part of the claimed design.

1 Claim, 5 Drawing Sheets
